UNITED STATES PATENT OFFICE.

ALFRED C. EINSTEIN, OF ST. LOUIS, MISSOURI.

ACETYLENE-GAS GENERATOR.

SPECIFICATION forming part of Letters Patent No. 752,053, dated February 16, 1904.

Application filed June 4, 1902. Serial No. 110,131. (No model.)

To all whom it may concern:

Be it known that I, ALFRED C. EINSTEIN, a citizen of the United States, residing in the city of St. Louis, in the State of Missouri, have invented certain new and useful Improvements in Acetylene-Gas Generators, of which the following is a full, clear, and exact description, reference being had to the accompanying drawings, forming part of this specification.

My invention relates to that class of gas-generating apparatus utilized in the production of acetylene gas from calcium carbid, the invention having for its object the production of a generator in which a normal pressure and amount of gas will be maintained, due to the construction and arrangement of the water-delivery parts of the apparatus and the connection of the gas-conveying pipes in such manner that the gas evolved in the apparatus constantly acts to regulate the amount of water fed to the carbid.

My invention consists in features of novelty hereinafter fully described, and pointed out in the claims.

Figure I is a vertical section of my generator. Fig. II is a horizontal section taken on line II-II, Fig. I. Fig. III is an enlarged view, partly in section, of the water and gas conducting tube and the water-feed pipe.

1 designates the generator-tank, to the lower end of which is detachably affixed the carbid-receptacle 2. The interior of the tank 1 is subdivided by partitions 3 and 4. The partitions 3 and 4 are united by a central tube 5, and the partitions divide the interior of the tank into three chambers—viz., a generating-chamber 6, in which the carbid is contained, a water-chamber 7, from which the water is conveyed to be delivered into the generating-chamber, and a gas-chamber 8, into which the gas passes as it is produced in the generating-chamber.

9 designates a water and gas conducting tube seated in the tube 5 and extending from the generating-chamber to the gas-chamber, the tube being open at both ends to communicate with said chambers.

10 designates a water-feed pipe provided with legs 11 and 12, that are open at their ends

to communicate with the water-chamber 7, so that water in said chamber may enter the legs to pass upwardly through the feed-pipe. The feed-pipe is preferably inclined upwardly from one of the legs, and it is positioned in 55 the conducting-tube 9 and provided with a restricted outlet-nozzle 13, through which the water finds egress from the feed-pipe into the conducting-tube to descend therethrough onto the carbid in the receptacle 2.

14 designates a supply-tank provided with an inlet 15, closed by a cap 16.

17 is a supply-pipe provided with a valve 18 and leading to the tank 1, to which it is connected at the bottom of the water-chamber 7. 65

19 is a drain-cock fitted to a supply-pipe 17.

20 is a relief-pipe connected to the supply-pipe 17 below the valve 18, that is positioned in said pipe and extends upwardly into the supply-tank 14 to the upper end of said tank. 70

21 is a blow-off at the top of the supply-tank.

22 is a gas-delivery pipe leading from the upper end of the generator-tank 1 and having communication with the gas-chamber 8. This delivery-pipe serves to convey the gas as it is 75 generated from the gas-chamber to the points of consumption, and it is preferably provided with a suitable regulator-23.

24 is a return gas-pressure pipe leading from the gas-conveying pipe 22 to the tank 1 80 and introduced into said tank at the upper end of the water-chamber 7.

In the conducting-tube 9 I provide one or more orifices 9^a, through which the condensed water resulting from vapor that rises into 85 the gas-chamber 8 from the generating-chamber may be returned to the generating-chamber on falling to the dished partition 4, which constitutes the bottom of the gas-chamber.

In the practical use of this generator carbid is placed in the receptacle 2 previous to its being affixed to the generator-tank, and on the application of the carbid-receptacle to the tank the apparatus is in condition for service. Water is introduced into the supply-tank 14 through the inlet 15 and passes therefrom through the supply-pipe 17 to the water-chamber 7 in the tank 1, the amount of water introduced being governed by the location of the inlet, which is positioned so that 90

95 water introduced being governed by the location of the inlet, which is positioned so that 100

the supply-tank will be only partially filled when the water-chamber is full. When the desired amount of water has been introduced, the valve 18 may be closed to shut off the 5 passage of water from the supply-tank to the water-chamber until such time as may be desired to effect generation of gas. On the opening of the valve 18 the water contained by the supply-tank descends through the 10 supply-pipe 17 and enters the water-chamber 7, with a result that it rises through one of the legs 11 or 12 of the feed-pipe 10 to escape through the restricted outlet-nozzle 13 and descends through the conducting-tube 9 15 into the generating-chamber onto the carbid in said chamber. While I have shown the feed-pipe 10 as provided with two legs, I do not limit myself to the use of both of these legs, as one of them would be ample under 20 many conditions. By the delivery of water to the carbid in the manner explained generation of gas is produced and the gas passes from the generating-chamber through the tube 9 into the gas-chamber 8 and generation being continued without cessation so long as excessive pressure is not produced. In the result of excessive pressure of gas the gas after passing into the conveying-pipe 22 returns to the generator-tank through the return pressure-pipe 24 and enters the water-chamber 7 25 to exert pressure against the water in said chamber. In such case the water in said chamber is driven downwardly therein by the pressure of gas and ascends through the supply- 30 pipe to be returned to the supply-tank 14, thereby lowering it away from the leg or legs of the feed-pipe 10 and causing cessation of delivery of water through said feed-pipe. The pressure of gas holds the water in the 35 chamber 7 away from the feed-pipe until the gas-pressure again becomes normal in the gas-chamber 8, when upon reduction of pressure the water returns to the water-chamber and delivery through the feed-pipe is again 40 established as before to renew the generation of gas.

In the event of excessive pressure of gas occurring after the apparatus has been shut

off by the closing of the valve 18, that controls the supply-pipe 17, the excessive pressure may find egress from the water-chamber 7 by passing through the water therein and through the supply-pipe 17 to the relief-pipe 20, through which it is delivered into the supply-tank 14 to escape through the blow-off or safety valve 21.

I claim as my invention—

1. In an acetylene-gas generator, the combination of a generating-chamber, a water-chamber, a gas-chamber, a tube providing communication between said generating-chamber and said gas-chamber, a feed-pipe having a leg arranged in said water-chamber and seated in said pipe, an outlet-nozzle on said feed-pipe in said tube, a supply-tank, a supply-pipe leading from said supply-tank to said water-chamber, a gas-conveying pipe leading from said gas-chamber, and a return-pipe leading from said gas-conveying pipe to said water-chamber, substantially as and for the purpose set forth.

2. In an acetylene-gas generator, the combination of a generating-chamber, a water-chamber, a gas-chamber, means for delivering water from said water-chamber to said generating-chamber, a water-conveying pipe leading from said gas-chamber, a return-pipe leading from said gas-pipe to said water-chamber, a supply-tank, a supply-pipe leading from said supply-tank to said water-chamber, and a relief-pipe leading from said supply-pipe into said supply-tank, substantially as described.

3. In an acetylene-gas generator, the combination of a generating-chamber, a water-chamber, a gas-chamber, a tube providing communication between said generating and gas chambers, and provided at the bottom of said gas-chamber with an orifice, a water-feed pipe leading from said water-chamber to said tube and having an outlet arranged in said tube, substantially as described.

ALFRED C. EINSTEIN.
